LOCK FOR LUGGAGE OR SIMILAR ARTICLE

Jon W. Hauser, St. Charles, Ill., assignor to Sol Koffler,
West Warwick, R. I.

Application June 16, 1955, Serial No. 36,538

Term of patent 14 years

(Cl. D87—2)

FIG. 2

FIG. 1

FIG. 3

FIG. 4

Fig. 1 is a top plan view of a lock for luggage or similar article, embodying my new design;

Fig. 2 is a rear elevational view thereof, taken along the line 2—2 of Fig. 1;

Fig. 3 is a side view thereof; and

Fig. 4 is a front elevational view thereof.

The side opposite that shown in Fig. 1 is substantially plain.

I claim:

The ornamental design for a lock for luggage or similar article, as shown and described.
